INVENTOR:

Ebner Leigh.

BY

ATTORNEY'S

UNITED STATES PATENT OFFICE.

ABNER LEIGH, OF ST. LOUIS, MISSOURI.

FLOOR-CLEANING DEVICE.

1,383,731.

Specification of Letters Patent. Patented July 5, 1921.

Application filed December 8, 1920. Serial No. 429,191.

To all whom it may concern:

Be it known that I, ABNER LEIGH, a citizen of the United States, residing at St. Louis, in the county of St. Louis City, State of

Missouri, have invented certain new and useful Improvements in Floor-Cleaning Devices; and I do hereby declare the following to be a full, clear, and exact description of the invention, such as will enable others skilled in the art to which it appertains, to make and use the same.

This invention relates to new and useful improvements in scrubbing devices and particularly to floor cleaning devices.

One object of the invention is to provide a device of this character whereby the scrubbing operation and the final mopping or drying operation may be accomplished by means of the same mechanism.

Another object is to provide a device of this character which is simple in construction, easy to operate, and whereby the operations of scrubbing and mopping can be accomplished from a standing posture.

Other objects and advantages will be apparent from the following description when taken in connection with the accompanying drawing.

In the drawing:

Figure 1 is a top plan view of the combined scrubber and mop.

Fig. 2 is a side elevation of the same.

Fig. 3 is a front elevation of the device.

Fig. 4 is a rear elevation of the device.

Referring particularly to the accompanying drawing, there is shown an elongated brush 10 to the center of the back of which is secured one end of a handle 11. The brush has the floor engaging bristles 12.

Disposed rearwardly of the brush is a clamping frame 13 in which is held a mop 14, the said frame being of a length approximately equal to that of the brush 10. Secured to the clamping frame 13, and extending longitudinally thereof, is an axle or

shaft 15, floor engaging supporting wheels 16 being carried by the ends of the said axle.

Connected to the handle 11, and extending to the ends of the clamping frame 13, are the braces 17.

Mounted on the handle is a receptacle 18 which is adapted to contain water, and extending from the forward lower end of this receptacle is a pipe 19 which terminates among the bristles of the brush for supplying water to the brush, as the device is moved back and forth over the floor. In the lower end of the receptacle is mounted a spring pressed valve 20 which prevents escape of water until unseated by the upwardly extending rod 21 which is secured to the valve 20, and has a handle 22 at its upper end, near the upper end of the handle 11, within convenient reach of the operator who holds the handle while moving the device across the floor.

In the scrubbing operation the mop is held out of contact with the floor by reason of the fact that it is somewhat higher on the handle than the brush, and when the mop is to be used the handle is moved downwardly until the mop touches the floor, when the brush end may be lifted from the floor.

Thus, by means of a single device, and without moving from a standing position, the operator can scrub and wipe dry a floor.

What is claimed is:

A floor cleaning device including a handle, a slidably adjustable collar on the handle having oppositely and downwardly extending arms, a frame connected with and supported by the arms, a mop supported in the frame, and floor engaging wheels carried by the ends of the frame.

In testimony whereof I affix my signature in the presence of two witnesses.

ABNER LEIGH.

Witnesses:

JOHN JONES,
WILL WILLIAMS.
